[57] **CLAIM**

The ornamental design for a canister bin, as shown and described.

DESCRIPTION

FIG. 1 is a side elevational view of a canister bin embodying my new design.

FIG. 2 is a front elevational view as on line 2 — 2 of FIG. 1.

FIG. 3 is a rear elevational view as on line 3 — 3 of FIG. 1.

FIG. 4 is an elevational view from the top and in the direction of line 4 — 4 of FIG. 1, the lid having been omitted.

FIG. 5 is a bottom plan view of the lid on an enlarged scale.

FIG. 6 is a cross-sectional view of the lid taken on line 6 — 6.

The bottom surface of the bin is flat.

FIG. 4

FIG. 3

FIG. 6

FIG. 5
